CLAIM

The ornamental design for a surgical portal driver, as shown and described.

DESCRIPTION

FIG. 1 is a top perspective view of a surgical portal driver showing our design;
FIG. 2 is a bottom perspective view thereof;
FIG. 3 is a top view thereof;
FIG. 4 is a first side view thereof;
FIG. 5 is a bottom view thereof;
FIG. 6 is a side view thereof, opposite that shown in FIG. 4;
FIG. 7 is another side view thereof, 90 degrees offset from that shown in FIG. 6;
FIG. 8 is another side view thereof, opposite that shown in FIG. 7; and,
FIG. 9 is a bottom perspective environmental view illustrating the surgical portal driver engaged with a working portal (also known as a guide cannula) of the present invention. In the drawings, the broken lines depict environmental subject matter only and form no part of the claimed design.
